HOSIERY FORMING AND DRYING DEVICE

Harold E. Stout, Reading, Pa.

Application November 22, 1940, Serial No. 366,602

3 Claims. (Cl. 223—76)

My invention relates to hosiery forming and drying devices, particularly of the internally heated type, and to means for, and methods of, producing novel functions in the construction, arrangement, support, weight, cost, operation, rigidity, safety, degree and distribution of heat, time of drying, fluid-pressure resistance, adaptation of hosiery of different forms, and other features.

Heretofore, it has been suggested to produce internally heated hosiery forms by casting them of aluminum with sand cores, in which the percentage of defective castings and losses therefrom, caused by thin walls and other factors, are unduly large.

Also, since aluminum casting is relatively porous, such prior devices, where fluid such as steam under pressure is employed as the heating medium, are subject to leakage, and the construction is such as to limit the steam pressure to very low values, and consequently, to reduce the degree of heat, and extend the time of drying hosiery.

Excess steam pressure, as from a defective reducing valve, has been known to cause violent bursting of such cast aluminum forms, causing considerable loss, and endangering the operators.

Such prior structure, by reason of the stated objections, was replaced by forms each constructed of pressed-steel half portions welded to each other, with a partition therebetween, in an endeavor to provide positive directional travel for the steam into the form at one end, therealong to a position adjacent to the other end, and back to the entrance.

The partition, although effectively welded to one of the form halves, is not effectively sealed to the other half, caused by welding difficulties with this particular construction, so that short-circuiting of the steam and air in the form occurs. The partition is also, only in the leg portion and in part of the foot portion, but not in the toe section, such that the steam does not traverse a uniform path, and does not adequately heat the toe portion, particularly where a replaceable or substitute toe portion, larger than a similar portion of minimum size, is in position.

Hosiery forms of such character are clamped to an arm or base, through which they receive the steam, whereby yieldable gaskets, as of rubber, must be employed between the forms and the bases, to compensate for expansion and contraction.

When the steam is shut off, contraction of the form and base causes the ingress of air at the

gaskets, which must be expelled before the steam is again applied, in order to ensure effective heating.

The likelihood of the above-mentioned short circuiting, caused by defective sealing of the partition to one of the form halves, renders it impossible to determine exactly how much air is trapped in the form to reduce heating, and increase the time of drying, the stockings.

The steel forms are heavy, more difficult to handle, expensive in manufacture, subject to rust, against which they must be protected at added cost, and have other disadvantages.

In another aspect, of all such prior devices, various attempts have been made to adapt certain parts of the form bodies to the reception of any of a selection of form elements varying the contour of the device as a whole, such as to adapt the same more effectively to stockings of different sizes, lengths and shapes.

Such attempts have various objections, such as holding the removable form elements to the base by friction alone, whereby they are not positively locked in position, may slip out of place, form air pockets, reduce the heating at the places of application, and are otherwise ineffective.

Others are of difficult manufacture, limited in the variety of forms, and have form elements which do not fit the bases effectively, are not close enough to the heating medium, have edges or corners likely to injure the fabric, and are difficult to handle.

Stocking forms of the aforementioned types are supported either stationarily or movably, in either case of which, and particularly in the movable type, difficulty has been had in rendering the support simple, effective, economical, durable, rigid, capable of adequate removal of moisture of condensation, non-interfering with the work of the operators, and free from other adverse features.

A support of the latter character, if in the form of an arm also constructed of cast aluminum, has the steam-pressure and leakage defects of the form and, if constructed of steel, is excessively heavy for operation in a group containing a large number of such forms, as is contemplated by the invention.

The invention hereof is proposed to overcome porosity, low fluid-pressure resistance, and other adverse features, as in the aluminum forms and bases or supports, and the objections to the steel forms and supports above set forth, in the feature of employing a main body material which may be of aluminum, or substantially the weight

and other character thereof, and have enclosed or embedded therein conduit means, such as copper tubing, to prevent leakage, provide for increased internal fluid pressures, render the structure light in weight, and avoid air trapping, as stated.

In a form of such character, in view of the stocking shape, and particularly where the structure is thin and contoured at its edges similar to the edges of a stocking in flat form, a very great difficulty resides in properly floating or centering the tube in the mold, irrespective of the material of the tube, whereby to ensure uniform cross sections of the molded material in its still thinner outer casing parts, and uniform heating at its surface.

Where the body material of the arm or form is molded about the conduit, and the body is of lower melting temperature than the conduit, as in the case of an aluminum body and a copper tube, further difficulty occurs, such that, if the temperature of the body material is not closely controlled, and other precautions, as hereinafter set forth, are not observed, the conduit will be pitted or rendered useless.

Among the objects of my invention are to overcome all of the difficulties and adverse features above mentioned, and to provide a device that shall effect such results at a cost of material, time and effort comparable to, or less than, the corresponding factors of the former devices.

Another object of the invention is to provide a light-weight hosiery form element of very greatly increased internal fluid-pressure resistance in consideration of such weight.

Another object of the invention is to increase the degree and uniformity of heat for, and decrease the time of, drying stockings on forms of the above-designated character.

Another object of the invention is to provide a stocking form, or stocking form base, and a support therefor, severally and together, and the method of making, or producing a novel function of, the same, whereby conduit means is effectively molded in a body or support of either or both, as by controlling the relative temperatures of the conduit and body, and supporting or centering the conduit in the mold by material fusible with the body, or by the mold and such material, as through the use of baked portions of the mold and added length sections of the conduit for support by said baked mold portions, and subsequent severing from the embedded conduit parts.

Another object of the invention is to provide a hosiery form adapted to receive a toe-form element, in which a circuit for a heating medium shall have a defined path leading into, making a return bend in, and leading from, an extension of the foot portion for receiving the toe-form element of the form, and severally therefrom or therewith be adapted, at a position inside such bend, for adequately holding the toe-form element to the body.

Another object of the invention is to provide for the reception and holding of form elements, other than the toe-form element, by means cooperating with the body at a position or positions intermediate spaced branches of the conduit aforesaid to provide effective anchorage or support for the holding means.

Another object of the invention is to provide a hosiery form body having an extension, as in the toe, constituting substantially a plug for a

form element in the shape of a socket made up of separate parts whereby to more accurately fit the plug, and ensure more effective heating of the element, and providing, severally therefrom or together therewith, one or more separate-part form elements, similar to the toe-form element, but through an opening between which the form body or base extends in a manner also ensuring more accurate fit and effective heating.

Another object of the invention is to provide a hosiery form core or base that shall be adapted to receive form elements of any conceivable shape, whereby such elements may be placed severally and in combination on the base according to any hosiery form that has been, or may be, devised.

Another object of the invention is to provide a novel hosiery form structure of the above-indicated character that shall be light in weight, of smooth outer surface contour, free from air pockets, edges and corners, simple and durable in construction, economical to manufacture, and effective in its operation.

Another object of the invention is to provide an internally heated hollow hosiery form base or body, which partly or entirely conforms only generally to a stocking form; or is partially or entirely non-stocking conforming, whereby certain or all of the stocking contour may be varied at will.

A further object of the invention is to provide a hosiery form arm or support that shall be more rigid, of increased internal fluid-pressure resistance, of improved cooperation as to weight and other factors with other elements and similar arms in a movable group of such arms, and with stationary forms, and provide easier, more rapid and effective removal of moisture or condensation, and have other advantages.

With such objects in view, as well as other advantages which may be incident to a utilization of the improvements, the invention comprises the parts and combinations thereof, hereinafter set forth in the drawings, specification and claims, with the understanding that the several necessary elements constituting the same may be varied in proportion, arrangement and texture, without departing from the nature and scope of the invention.

In order to make the invention more clearly understood, means are shown in the accompanying drawings for carrying the same into practical effect, without limiting the improvements, in the useful applications thereof to the particular constructions, which for the purpose of explanation are made the subject of illustration.

In the drawings:

Figure 1 is a top plan view of the drag of a flask in which one example of the invention is molded, showing the bottom half of the mold impression, the gate passageways and the riser, together with a conduit held in position by means, in this instance, including parts of the mold itself, and chaplets having parts fusible with the molded body;

Fig. 2 is a sectional detail view, on an enlarged scale, taken substantially along a line 2-2 of Fig. 1, but also showing parts of the cope along this line;

Fig. 3 is a perspective view of the chaplet elements shown in Fig. 2;

Fig. 4 is a view, in side elevation, of the product of the mold of Fig. 1, after finishing operations have removed portions of the gate material, the

chaplets and conduit sections employed in supporting the conduit in the mold;

Fig. 5 is an enlarged sectional view, taken along the line 5—5 of Fig. 4;

Fig. 6 is an elevational view, taken along the line 6—6 of Fig. 4;

Fig. 7 is a greatly enlarged view, in side elevation, including a small portion of the extreme upper end of the structure of Fig. 4, a toe-form element shown in full lines thereon, and a number of alternate toe-form elements therefor indicated in dot-and-dash lines;

Fig. 8 is a view taken substantially along the line 8—8 of Fig. 7;

Fig. 9 is a view similar to Fig. 4, but with a toe-form element in place, of the invention in modified form adapted to receive toe, foot and leg elements of any desired form throughout its length from a base end thereof;

Fig. 10 is a view, in inner side elevation, of a half form element, or one of two separate members making up such element; the half form element or member in this instance being for attachment to the form base of Fig. 9 at the rear side thereof, under the foot portion shown, for cooperation therewith, and with the other half form, to adapt the structure to receive half hose;

Fig. 11 is a view, similar to Fig. 10, of a rear half member of a form element for adapting the structure of Fig. 9 to receive a full length stocking;

Fig. 12 is a top plan view of a rear half form element similar to that of Fig. 11, but adapted to stockings of greater width in the calf and welt;

Fig. 13 is a front elevation or inside face view of the half form of Fig. 12;

Fig. 14 is an inside face view of a rear half member of a foot form element similar to that of Fig. 9, but having rounded lower edges adapting the device to receive very short hosiery or anklets;

Fig. 15 is a view similar to Fig. 11 or Fig. 13, of another rear half form member for full length hosiery in which a further special shape is desired;

Fig. 16 is a view similar to Fig. 14, of another modification of the foot form member;

Fig. 17 shows a leg form, similar to those of Figs. 11, 13 and 15, but having an enlarged portion along its lower front edge;

Fig. 18 is a view of the rear half of a modified toe-form element, similar to the corresponding element of Fig. 7, but enlarged at its upper side;

Fig. 19 is a top plan view of a modified form of the invention applied to an arm or base for supporting the device of Figs. 4 or 9, showing also a portion of a heating-medium distributor therefor;

Fig. 20 is a view, in side elevation of the structure of Fig. 19; and

Fig. 21 is an enlarged detail sectional view, taken substantially along the line 21—21 of Fig. 19.

Referring to Fig. 1, a flask or mold structure M includes a lower sand mold member or drag D, in which is located half of an impression A of a hosiery form of the invention, minus a toe-form element hereinafter set forth.

Also impressed in the drag, are a portion providing a gate space 25, and a portion defining a riser or air escape space 26.

The other half of the form impression A is formed in a cope C, or upper half of the flask M, a portion of which is shown in Fig. 2, and which

has similar spaces or impressions of the gate 25 and the riser 26.

The molded product or body B, in this instance, is shown in Fig. 4 as a form for receiving half hose, after the mounting of a toe-form element T, shown in Fig. 7, on a plug end or extension E of a foot portion F, also having a heel portion H, and disposed on a leg portion L having a lower length 27, and a base plate portion 39.

10 In the structure B of Fig. 4, a conduit 31, in this instance of copper, is of return-bend form having its bend 32 and portions adjacent thereto in the extension E lengths 35 extending spaced from each other from the bend through the foot portion F, at a foot angle to the leg portion L, to lengths 36, also spaced from each other in the leg portion L and the lower length 27.

All of the conduit 31, except short lengths 37 thereof, of circular cross section near the bottom of the device, as seen in Fig. 4, is flattened to substantially oval cross section in a front-to-back median plane of the device, as better seen in Fig. 5.

Reverting to Fig. 1, the conduit 31, which is initially longer than in its form of Fig. 4, to the extent of additional lengths 40 of circular cross section, is placed in the drag D, as shown, with the lengths 40 supported in impressions in baked sand insert portions 42 in the sand of the drag and cope for this purpose.

Prior to such placing of the conduit however, the drag is provided with lower chaplets 41, see also Fig. 2 and 3, each comprising a lower member 45, as of strap steel, having end lengths 46 bent at angles to the body thereof and embedded in the drag. This member is spaced clear of the mold form impression A, as indicated in Fig. 2.

A metal stamping 47 having depending legs 50 secured to the member 45 in slots thereof, has portions 51 spacing the side-by-side lengths or legs of the conduit from each other. The stamping 47, which in this instance is of aluminum, is adapted to fuse to, or into, the metal forming the molded body B of the device of Fig. 4.

45 Upper chaplets 55 each comprises a member 56 similar to the member 45 having angularly bent end lengths 57 embedded in the cope C, and is also spaced clear of the mold form impression A.

A metal stamping 60 is secured to the member 56 similarly to the manner in which the stamping 47 is secured to the member 45, but instead of the conduit seating and centering portions 51 and 52 of the chaplet 41, is of flat or plane form engaging the top flat sides of the conduit legs between upwardly projecting parts of the stamping 47.

The stamping 60 is, in this instance, also of aluminum for fusing to, or into, the metal forming the molded body of the device of Fig. 4.

60 With one pair of chaplets firmly holding the conduit near the toe end of the mold, another pair of chaplets similarly holding the conduit in the leg portion near the foot portion of the mold, and the added circular conduit end lengths 40 held directly by the drag and the cope, through the intermediary of the baked sand inserts 42, the molding material is poured into the gate 25, from which it spreads to all parts of the impression A.

With the molding material of aluminum, as it is in this example, which is of lower melting point than the copper, such material is poured at substantially the lowest temperature at which it will properly flow and produce an effective molded body around the conduit, which

is preheated to avoid wide difference of temperature, and to prevent warping and other damage, such as pitting the surface, or weakening the texture, of the conduit side walls.

The conduit outer surface may be treated, as by coating with chalk or tin, to avoid the formation of gas upon contact with the molding material, or to provide more intimate contact or joinder between such material and the conduit.

During the molding, the aluminum portions 47 and 60 of the lower and upper chaplets 41 and 55, respectively, are fused to, or into, the main aluminum body mold such as to become homogeneously integral parts thereof, without causing fissures or other weakness therein.

After removal of the product from the mold, the added circular section end lengths 40 of the conduit 31 are severed, the gate portions of the body and the protruding chaplet portions removed, and the product given a smooth contour and finish, as indicated in Figs. 4 and 5.

The cross section of Fig. 5, taken through the leg portion near the heel portion of the form, indicates the accurate centering given the conduit by the method hereof, relative to both the relatively flat thin sides and the relatively sharp, although rounded, front and back edges of the form. The latter maintains a similar section throughout, but varying in distance from front to back, with respect to all of which the conduit is symmetrically maintained. The conduit, which in this instance, conforms only in general to the foot and leg portions, may, of course, be bent to conform substantially exactly to these portions, as well as to the heel.

Attention is also directed to the relation of the conduit 31 to, and its position in, the toe extension E, Figs. 4 and 6, wherein, irrespective of the thinness of the molded body webs, the conduit is accurately centered. All of the extension surface portions, and of the transverse end surface of the foot portion at the base of the extension, are accurately dressed to closely fit the toe-form element T, better shown in Figs. 7 and 8.

In order that the element T may accurately fit the plug or extension E, and avoid uneven heating through irregularly engaging surfaces and air pockets, it is constructed of separate halves, or plates, 61 and 62, constructed, in this instance of aluminum, and divided from each other along the median front-to-back stocking plane, each having a depression cooperating with the depression of the other to form substantially a socket for the plug. The opening in this socket could only be formed, if at all, in a solid single piece of metal, by the expenditure of great effort, skill and expense.

Other form elements, for other parts of the device, to be hereinafter set forth, are formed of similar complementary separate halves or plates, for separate manipulation in mounting on a modification of the body, but, in the case of the toe-form element, by reason of its position at an end of the device, the half members, as shown in Figs. 7 and 8, are permanently joined to each other, as by rivets 64 having end surfaces smooth flush with the stocking-receiving surface of the element.

The fit of the element T on the extension E is such as to be snug when the device is at operating temperatures, and easily removable and replaceable when cool, whereby to ensure effective heat transfer, and to avoid friction resistance or effect during removal and replacement.

The half toe-form member 61 and the extension T are provided in this instance, with apertures for register with each other along an axis just inside the bend of the conduit, or in other words, intermediate the branches of the conduit, for the reception of a screw 65, which is adapted for cooperation with an insert 66 in the member 62 on the aforesaid axis. The insert 66 is of material, such as stainless steel, to provide screw threads in the member 62 for the screw 65, stronger than the same threads in the aluminum member, and is securely held in position, as by having its opposite end edges swaged, or otherwise formed, to interlock with the insert with the member axially of the screw.

This arrangement of rendering the means for securing the toe-form element to the body or base operative at position intermediate the conduit branches or legs, enables such means to be a screw or other device, which is impossible in the prior hollow forms having thin walls and no material, as herein, with which such means or screw could effectively cooperate.

The head of the screw 65 is arranged to avoid injuring the fabric, as by being slightly within the outer toe form surface, or free from slot edges at its periphery.

The outer surface of the insert 66 is similarly arranged, as by being smooth flush with the outer surface of the form.

As illustrated by dot-and-dash lines in Fig. 7, toe form elements of various sizes and lengths, but otherwise like the form T above set forth, may be provided to accommodate hosiery of corresponding toe sizes or lengths.

In the form of Fig. 4, the device is all in one permanently united structure, except the toe, and adapted to only one general form of stocking, namely half hose.

In Fig. 9, a conduit 79, similarly to the conduit 31, has only general leg and foot form, and a body 71, in which the conduit is molded, instead of having any parts exactly conforming to any particular stocking shape, has its parts molded all over the conduit of rectangular cross section similar to that of the extension T, although this section may be modified in both instances.

By this arrangement, not only may the toe-form T be employed at the toe end of the body 71, but this body may receive foot, heel and leg form elements of an infinite variety of shapes and sizes, to accommodate the device to any conceivable stocking.

As seen in Fig. 9, in addition to the removable toe-form element T, there is shown a removable foot-form element 72, also made up of complementary halves or plates of the cross section of Fig. 8, and secured in position, as by screws 75 like the screws 65. The element 72, in this instance, has lower corners whereby it may continue the contour of leg-form plates 76, one of which is shown in Fig. 10, for adapting the device to the reception of half hose.

The element 72 is similarly constructed for cooperation with leg-form plates 77, one of which is shown in Fig. 11, to adapt the device to hosiery of full length.

As seen in Figs. 12 and 13, one of a pair of plates 77, having a portion 80, at its rear side, adding width thereto, is likewise adapted for position on the form body 71 to adapt the device to full length stockings having greater width in the upper legs and welts.

Fig. 14 shows a plate 81 somewhat like one of

the plates 72 of Fig. 9, but having rounded bottom edges 82, whereby a pair of such plates cooperate only with a toe-form element to adapt the device to very short stockings or anklets.

In Fig. 15, a leg-form member 85, for mounting on the body 71 of Fig. 9, has a rear edge 86 whereby the device is adapted for receiving stockings of special shape.

Fig. 16 shows a foot-form member 87, similar to the member 81 of Fig. 14, but having a portion 90 for wider stocking soles, a portion 91 for larger stocking heels, and a portion 92 for wider stocking ankle or leg portions.

In Fig. 17, a full-length leg-form element 95, similar to the plates of Figs. 11, 13 and 15, has a front edge portion 96 rendering the same wider in the calf and welt.

Fig. 18 shows a modified toe plate 97 having an upper side portion 98 disposed farther from the longitudinal center line than the lower side, thereby adapting the toe element to stocking toe portions of larger size in this dimension than the previously shown toe-form elements.

The above-given examples do not represent all of the forms which may be produced according to the invention, but only a sufficient number of them to indicate the complete universality of the variety which may be obtained.

In Figs. 19 and 20 is shown a supporting arm S, for the structures of Figs. 4 and 9 above set forth, constructed in accordance with features of the invention hereof, and, in other features, being an element of the invention set forth in the copending application of Frank Y. Kitzmiller, Serial No. 354,152, filed August 26, 1940, on Fabric drying and shaping apparatus and method, to which reference should be had for a better understanding hereof.

The arm S is constructed of metal, such as aluminum, having tubes 100 and 101, as of copper, cast therein, as above set forth relative to Figs. 1 to 6, inclusive, with the tubes sloping upwardly and outwardly from a drum J to an outer end portion 102 of plate-like character for receiving a gasket 105, and the body B, as shown, or the body 71 of Fig. 9.

Screws or bolts 106 extend through openings 107 in the portion 102 of the arm S, the gasket 105, and the base plate portion 30 of the body B for securing the body B and the arm S together, with the tubes 100 and 101 in register with the lengths 37 of the conduit 31.

The slope of the tubes 100 and 101 is provided, whereby these tubes not only constitute means for transmitting a heating medium, such as steam, from the drum J to the body B and back to the drum, but as drain means for moisture of condensation in the arm and the form.

As shown, the arm S is of hollow section for strength, tapering from relatively large cross section near the drum J to smaller cross section adjacent to the outer end portion 102, having three-screw attachment portion 110 for connection to the drum, with the tubes 100 and 101 in register with apertures in the drum, and sealed as by a gasket 112.

Near the drum J, the arm S has flat-plane bottom side webs 109 for mounting on a turn-table, and slotted bosses 115 on the webs adapted to receive bolts or screws for adjustably securing the arm to the table.

The tubes 100 and 101, which are disposed one above the other through most of the arm, diverge laterally near the outer end of the arm, as indicated in Fig. 19, to positions of register with

the respective branches or legs of the conduit 31 in the body or form B.

Several of such forms are arranged radially of the drum J, whereby an operator may freely work on one, by moving her hands and arms upwardly and downwardly between the one on which she is working and the next adjacent forms at either side thereof, without contact with, or burning from, the forms; or from obstructions between the forms or arms, as exist in prior devices of this general nature.

In this instance, steam is the heating medium, which, by reason of the molded-in conduit construction of both the form B and the arm S, may be supplied under pressure as high as, or higher than, one hundred pounds, as against the twenty or thirty pounds or generally lower limits of former cast aluminum forms, and therefore improving the device in this feature to the extent of about three hundred to five hundred per cent, with the consequent acceleration to the time of drying, and the resultant increased output and economy.

The drum J, as better shown and described in the above-mentioned copending application, comprises, as here shown, an outer peripheral wall 116, upper and lower end closure walls 117 and 118, respectively, and a wall 119 intermediate the walls 117 and 118, thereby providing a distributor chamber between the walls 117 and 119 communicating with the outgoing live steam conduit 100, and a collector chamber between the walls 119 and 118 communicating with the spent steam return conduit 101.

Moisture of condensation drains from both branches of the conduit 31, the tubes 100 and 101 to the distributor and collector chambers of the drum J, and downwardly on the slightly inwardly sloping walls 119 and 118 through drain openings therein to an outlet conduit.

For further manufacturing facility, simplicity and strength, and effective operation and other advantages, the drum J may have its outer surface of the well 116 of polygonal character having an annular series of flat surfaces corresponding to the number of the arms J, which, in such case, will also have flat inner end surfaces for cooperation with the flat surface portions of the drum.

Fig. 21 shows the lower end of the body B, and of one of the branches of the conduit 31, each of which conduit branches is provided with a laterally outwardly extending flange portion 122 seated in a recess in the base plate 30 of the body B.

Each of the tubes 100 and 101 has a similar laterally outwardly extending end flange portion 123 in a recess in the plate-like portion 102 of the arm S, whereby with the gasket in position engaging the broad area surfaces of the flanges 122 and 123, as shown, steam pressure is maintained farther from the areas of division between the copper and aluminum parts than it would be if the conduits were merely severed at the ends, and a strong and effective joint structure is produced and maintained. The flanges 122 and 123 are substantially flush with the end surfaces of the body B and the arm S, respectively.

A similar arrangement may be provided at the opposite ends of the tubes 100 and 101, for similar operation in the arm S, and cooperation with the gasket 112 and the drum J.

The device is very effective and safe in operation, provides a flexibility heretofore unknown in

its ready adaptation to stockings of every conceivable size and shape, dries the stockings considerably more uniformly and rapidly, and is of substantial improvement generally in the field to which it relates.

I claim as my invention:

1. A hosiery forming and drying device comprising a return-bend copper conduit having free end lengths of circular cross section and the remainder thereof with flattened sides and lengths next to the bend at a foot angle to remaining leg lengths, an aluminum body molded about the conduit having form-element receiving portions including a toe-form element receiving extension and apertures through the body between said flat-side conduit lengths, and aluminum toe and leg form elements each including separate members fitting the corresponding receiving portion at opposite sides of the body, one member of each said elements having a screw-receiving portion and the other an aperture for register with the corresponding said body aperture for the reception of a screw for holding the form elements to the body.

2. In a hosiery forming and drying structure, a molded arm including means at one end for cooperation with heating-medium distributor means, form-supporting means at the other end, tube means embedded in the molded arm for conducting the heating medium from the distributor means to said supporting means, a molded hosiery form base including leg and foot portions for mounting on said supporting means and having form-element receiving means, form element

means for said receiving means, conduit means embedded in said base element communicating with the arm tube means, ends of the arm tube means and the form conduit means having laterally outwardly extending flanges flush with the adjacent surfaces of the arm and the form, respectively, gasket means on said surfaces, and means for securing the arm and the form in position and clamping the gasket means against said flanges and said surfaces.

3. A hosiery forming and drying device comprising a return-bend conduit providing legs having free end lengths of certain cross section and a remainder thereof with sides pressed laterally inwardly relative to said section rendering said remainder flatter than said free end lengths, said flatter portion having side-by-side lengths next to said bend spaced from each other and disposed at a foot angle to the remaining leg lengths, a metal body molded about the conduit preventing dead air space between said legs having toe form element receiving portions and means on the body in the region between said side-by-side flat side foot-angle lengths providing for securing separate members of a toe form element to the body, and a metal toe form element including separate members fitting said receiving portions at opposite sides of the body, each member of said element having a portion for register with said last named means and cooperating therewith to provide for completing the securing of said members to the body.

HAROLD E. STOUT.
